UNITED STATES PATENT OFFICE.

HERMAN E. HEINE, OF MILWAUKEE, WISCONSIN, ASSIGNOR TO BRADLEY WASH-
FOUNTAIN COMPANY, OF MILWAUKEE, WISCONSIN, A CORPORATION OF WISCONSIN.

SPRAY-HEAD VALVE.

Application filed February 13, 1925. Serial No. 8,913.

This invention relates to improvements in spray head valves more particularly adapted for use in connection with washfountains.

In washfountains now in general use, in factories and similar places the fountain is of circular shape to provide for a number of persons washing at the same time and to permit this a circular line of fine jets of water is discharged from the head of the wash-fountain. At times, however, only one or two persons may wash at the same time with the result that as the water is flowing all around the fountain, a considerable amount of the flowing water is not used and is wasted.

It is one of the objects of the present invention to overcome the before-mentioned objectionable features and provide a spray head valve which is formed with a number of spray sections which may be controlled by the users to discharge water from one or more sections as desired.

A further object of the invention is to provide a spray head valve in which the flow of water from the different sections is controlled by a single valve.

A further object of the invention is to provide a spray head valve in which means are provided for indicating the position of the valve handle with respect to the control of the sections.

A further object of the invention is to provide a spray head valve which is of simple construction, is strong and durable, and is well adapted for the purpose described.

With the above and other objects in view, the invention consists of the improved spray head valve and its parts and combinations as set forth in the claims and all equivalents thereof.

In the accompanying drawing in which the same reference characters indicate the same parts in all of the views:

Fig. 1 is a side view of the improved spray head valve;

Fig. 2 is a horizontal sectional view thereof taken on line 2—2 of Fig. 1, showing all of the water sections closed off;

Fig. 3 is a vertical sectional view thereof taken on line 3—3 of Fig. 1; and

Fig. 4 is a horizontal sectional view taken on line 4—4 of Fig. 1.

Referring to the drawing, the numeral 5 indicates a vertically extending water supply pipe which projects upwardly from a

circular washfountain or basin and at its upper end a spray head 6 is mounted. The spray head is of circular formation and comprises the upper member 7 formed with a downwardly extending annular flange 8 which extends over and has a threaded engagement with the lower member 9. Said lower member 9 is threaded on the upper end of the pipe 5 and is formed with an opening 9' registering with the bore of the pipe and on the upper face of the said lower member an annular groove 10 is provided to form a valve seat 11 which is engaged by a valve 12. The flange 8 of the upper member is provided with an outwardly projecting rib 13 which is formed with a circumferential line of downwardly inclined radial jet or spray openings 14 extending through the flange and rib. The upper member 7 is formed with an inner circular partition 15 which is positioned in eccentric relation to the upper member to form a valve casing for a rotary valve 16 mounted therein. The upper member is also provided with radial partitions 17 extending from the annular flange 8 to the circular partition 15 to divide the head into four water compartments, 18, 18', 18² and 18³ of equal size circumferentially. The circular partition 15 is provided with ports 19 extending through the partition which register with the elongated port 20 of the valve 16 in successive order as the valve is turned. The valve port 20 extends approximately around one half the diameter of the valve and the ports 19 are all positioned within one half the diameter of the circular partition or valve casing 15 so that with the valve in the position shown in Fig. 2, the water supply to all of the compartments will be closed. Now by turning the valve anti-clockwise with reference to Fig. 4, the port 19 to compartment 18 will first be opened and water will be supplied to one quarter of the spray head which is sufficient to supply several persons with water for washing. If a greater number desire to wash at the same time, the valve is further turned to supply water to the port of compartment 18' and when this is done, water will be discharged from one half of the spray openings to accommodate more persons. A further turning of the valve will open the supply to compartment 18² and 18³ as desired.

A valve stem 21 extends upwardly through

the upper member 7 and is provided with a handle 22 for convenience in turning the valve, and the upper member 7 is provided with spaced characters 23 to indicate the position of the valve.

10 The valve 12 is mounted upon the lower end of a valve stem 24 which extends upwardly through the upper member 7 and is provided with a handle 25 on its upper end for convenience in turning.

Stop members 26 are provided in the rotary valve 16 which are positioned to engage the valve stem 24 to limit the movement of said valve 16.

15 Stuffing nuts 27 and 28 are provided for the valve stems 21 and 24 respectively to prevent leaking of water around the said stems.

20 In use the valve 12 controls the flow of water to the spray head while the valve 16 controls the number of compartments or sections from which the water is discharged.

25 The water in passing from the valve 16 through the ports and into the compartments will lose considerable of its pressure and be discharged from the jet opening in a manner to avoid splashing when playing on the hands of the persons washing.

30 From the foregoing description it will be seen that the spray head valve is of very simple construction, is strong and durable and well adapted for the purpose described.

What I claim as my invention is:

35 1. A spray head valve, comprising a casing member having a plurality of jet openings, partitions dividing the casing member into a valve casing entirely within the casing member and three or more compartments in register with the jet openings, said compartments entirely surrounding the valve casing and said valve casing having an inlet opening and ports opening into the compartments, and a valve member within the valve casing and having a port, said valve member being movable to register its port with the valve casing ports to direct a fluid into one or more or all of the compartments.

40 2. A spray head valve, comprising a casing member having a plurality of jet openings extending around the outer side portion, partitions dividing the casing member into a valve casing and also into three or more compartments in register with the jet openings, said compartments entirely surrounding the valve casing and said valve casing having an inlet opening and ports opening into the compartments, and a valve member within the valve casing and having a port, said valve member being movable to register its port with the valve casing ports to direct a fluid into one or more or all of the compartments.

45 3. A spray head valve, comprising a two part casing member having a fluid inlet opening and a plurality of peripheral jet

openings, partitions dividing the casing into a valve casing and also into three or more compartments in register with the jet openings, the fluid inlet opening, opening into the valve casing space, said compartments entirely surrounding the valve casing and said valve casing having ports opening into the compartments, a valve member within the valve casing and having a single elongated port, said valve member being movable to register its port with one or more or all of the valve casing ports to direct the fluid into one or more of the compartments, means within the valve casing and extending above the casing member for controlling the flow of the fluid into the valve casing space, and means for turning the valve member.

4. A spray head valve, comprising a two part circular casing member having a fluid inlet opening and peripheral jet openings, partitions dividing the casing into a circular valve casing in eccentric relation to the casing member and also dividing the casing into three or more compartments in register with the jet openings, said compartments entirely surrounding the valve casing and said valve casing having ports opening into the compartments, a cylindrical valve member within the valve casing and having a single port, said valve member being movable to register its port with one or more or all of the compartments, a valve for the casing inlet opening and having a stem which extends upwardly through the casing, and means extending upwardly through the casing for turning the cylindrical valve.

5. A spray head valve, comprising a two part circular casing member having a fluid inlet opening and peripheral jet openings, partitions dividing the casing into a circular valve casing in eccentric relation to the casing member and also dividing the casing into three or more compartments in register with the jet openings, said compartments entirely surrounding the valve and said valve casing having ports opening into the compartments, a cylindrical valve member within the valve casing and having a port, said valve member being movable to register its port with one or more or all of the compartments, a valve within the cylindrical valve for controlling the casing member inlet opening and having a stem which extends upwardly through the casing, a valve stem connected to the cylindrical valve and extending upwardly through the casing, and means above the casing member for indicating the position of the cylindrical valve.

6. A spray head valve, comprising a two part circular casing member having a fluid inlet opening and peripheral jet openings, a cylindrical valve casing partition within the casing and in eccentric relation thereto and having parts extending therethrough,

other partitions connected to the valve casing partition and to the outer portion of the circular casing member and dividing said casing member into three or more compartments extending entirely around the valve chamber and in register with the valve casing ports and the jet openings, a cylindrical valve within the cylindrical partition and having a port, said cylindrical valve being movable to register its port with one or more or all of the ports of the cylindrical valve casing and having a stem which projects up-

wardly through the casing member, a valve within the cylindrical valve for controlling the casing member inlet opening and having a stem which extends upwardly through the casing member, handles for said valve stems, and characters on the casing member for indicating the position of the cylindrical valve.

In testimony whereof, I affix my signature.

HERMAN E. HEINE.
